ANTENNA FOR MOVING VEHICLES

William G. Dunn, Clarinda, Iowa

Application June 7, 1937, Serial No. 146,704

5 Claims. (Cl. 250—33)

My invention has to do with an antenna particularly adapted for use on moving vehicles, such as motor vehicles, boats, airplanes and the like.

More particularly it is my object to provide an antenna of this kind mounted to permit the antenna to lie in position close to the car body when the car is standing or traveling at low speed, and to be moved to a distance farther from the car when the car is traveling at higher speeds.

With these and other objects in view, my invention consists in the construction, arrangement and combination of the various parts of my antenna for moving vehicles, whereby the objects contemplated are attained, as herein-after more fully set forth, pointed out in my claims, and illustrated in the accompanying drawing, in which:

Figure 1 is a top or plan view of a part of an automobile equipped with a radio antenna embodying my invention.

Figure 2 is a front elevation of the same.

Figure 3 is an enlarged plan view of the mounting structure, parts being shown in section and parts being broken away.

Figure 4 is a detail sectional view taken on the line 4—4 of Figure 3.

Figure 5 is a side elevation of a different form of antenna.

Figure 6 is a top or plan view of the mounting structure of the device shown in Figure 5; and

Figure 7 is a detail sectional view taken on the line 7—7 of Figure 6.

Many attempts have been made to provide satisfactory antennae for moving vehicles and particularly for automobiles.

At low speeds, a very ordinary antenna is sufficient to catch the radio signals as is later made useful by the radio receiving set within the vehicle, but at increasing speeds, due to the sound or rushing of air past the vehicle, and also due to the increased vibration and noise of the mechanical parts of the vehicle, it is found that a more efficient aerial is then necessary.

It has been found that by raising the aerial away from the metal parts of the vehicle as nearly a 90° angle as possible that this efficiency is obtained.

In order to meet this problem, aerials of the "buggy whip" type have been provided. They have been fairly efficient but they have not been entirely satisfactory because of the fact that they project from the car in an objectionable fashion which often prevents them from be-

ing driven into a low doorway of a garage and so forth.

I have solved the problem by providing an antenna adapted to lie flat where it will be out of the way when the car is not moving or is traveling at low speed, the antenna being provided with means for taking advantage of the air pressure available when the car is traveling, for raising the antenna and moving it away from the car. Thus the antenna will have its maximum efficiency when the car is traveling at high speed when maximum efficiency is most necessary for the proper operation of the radio set.

I have shown in my drawing two forms in which my invention may be embodied, and to illustrate the fact that it may have a variety of embodiments.

In the particular form shown in Figures 1—4 a metal case shaped a good deal like a half of an egg shell, open at the bottom and indicated generally by the reference numeral 10, is shown secured to the top of a car 11 by means of screws 12.

Journalled in the walls of the case 10 are parallel shaft-like members 13, preferably made of stiff wire which form parts of wing-like antenna members A, each having generally the shape of the outline of a wing and being formed by means of wire material. The members 13 are secured together by small gears 14.

The rear ends of the antenna A normally lie on the top of the car 11, as indicated in Figure 1 and in full lines in Figure 2.

At the rear ends of the wing-like antenna members A they are provided with blades 15 or the like, which may be of metal or other suitable material, so shaped and arranged as to be engaged by the wind or air when the car travels at considerable speed, whereby the antenna members will be raised from their full line position shown in Figure 2 to their dotted line position shown in that figure.

Thus when the car is stationary or traveling slowly, the antenna will be down lying close to the car top, and when the car is traveling rapidly, the antenna will automatically be raised so that both members thereof will stand nearly upright for thus serving most efficiently the purpose of an aerial.

The gears 14 are blank for a considerable portion of their circumference, so that they can rotate for only certain distances. They are so arranged that they partially support the antenna members when the latter are in their lowered

position to keep them from wearing on the car top, and they are also so shaped that when the antenna members have swung to their full line position, shown in Figure 2, they can move no closer together.

An antenna of the kind just described is simple and inexpensive to construct. It is not in the way when the car is standing in the garage or being moved slowly into the garage. It is amply efficient to operate the radio when the car is not traveling at high speeds.

Its construction is such that the antenna members are raised to project away from the car when the latter is traveling at high speeds for thus giving maximum efficiency when such efficiency is most necessary.

In Figures 5 to 7 I have shown another form of antenna. In this form of device a bracket 16, comprising a bottom member 17 and laterally spaced side members 18, is mounted on the car top.

In this form of device the antenna is a suitable wire loop or U-shaped member 19 having long arms, the forward ends of which are curved upwardly and forwardly as at 20 (assuming the antenna to be in its down position), and journaled on a cross pin 21 mounted in the upper parts of the side members 16.

Another pin 22 is mounted in the side walls 18 below and rearward with relation to the pin 21.

Pivotedly mounted on the sides 18, by being mounted on the pin 22, are arms 23 standing below the curved portions 20 and oppositely curved. The arms 23 extend forwardly and normally lie close to the body of the car 24. These arms at their forward ends carry a blade 25.

A spring 26 is arranged on the pins 21 and 22 and is connected with one of the arms of the yoke 19 in such manner as to help lift that yoke and cushions its downward movement, and to tend to hold it spaced just above the top of the car.

Normally when the car is standing or moving slowly, the antenna 19 and the operating blade 25 assume approximately the positions shown in Figure 5. When, however, the car travels at considerable speed and it is desirable to have the highest efficiency from the radio, the rush of air from in front of the windshield against the under side of the blade 25 will cause the blade 25 to move upwardly. This causes the curved rear ends of the arms 23 to engage the

curved portions 20 and raise them up for lifting the antenna to its dotted line position of Figure 5.

This structure has all the advantages of the first described embodiment of my invention.

It should be mentioned that the usual precautions are taken and arrangements made in mounting the antenna. The casing 10 and the bracket 16 are insulated from the car body and the lead-in wires are connected to the antenna proper and to the car body in the ordinary way.

As will be seen from the double illustration of my invention, various changes may be made in the construction and arrangement of the parts, and it is my intention to cover the invention as broadly as may be in my claims.

I claim as my invention:

1. In a structure of the class described, an antenna member, means for pivotally supporting it on a moving vehicle, and means operatively associated with it adapted to be air actuated for raising the antenna on its pivot when the vehicle is traveling.

2. An antenna for moving vehicles, means for mounting the antenna for movement toward and from the vehicle, a blade operatively associated with said antenna and adapted to be actuated by air when the vehicle is moving to move the antenna away from the vehicle.

3. The combination of an antenna, with means for mounting it pivotally on the top of a vehicle, a blade operatively associated with the antenna, arranged to be engaged and moved by air when the vehicle travels at high speed, for raising the antenna toward upright position.

4. An antenna for moving vehicles combined with means for pivotally mounting same on a vehicle, a member arranged to contact the air and move the antenna away from the vehicle when same is moving rapidly forward and allowing it to lie relatively close to the vehicle when same is moving forwardly slowly, backwardly, or stopped altogether.

5. The combination with an antenna, adapted to normally lie relatively close to the surface of a vehicle when the vehicle is moving backwardly, stopped entirely or traveling slowly in a forward direction, and of a pivoted member adapted to contact the air and be moved away from the surface of said vehicle when it reaches a predetermined forward speed, and to move the antenna away from the vehicle.

WILLIAM G. DUNN.
